UNITED STATES PATENT OFFICE.

ADOLPH W. KREUTER, OF GRAND RAPIDS, MICHIGAN.

HARNESS-LOOP.

No. 895,376.

Specification of Letters Patent.

Patented Aug. 4, 1908.

Application filed November 25, 1907. Serial No. 403,813.

To all whom it may concern:

Be it known that I, ADOLPH W. KREUTER, a citizen of the United States, residing at Grand Rapids, in the county of Kent and State of Michigan, have invented certain new and useful Improvements in Harness-Loops, of which the following is a specification.

My invention relates to improvements in harness loops, and its objects are: first, to provide a loop for use upon the breast collar and breeching of a harness that will so strengthen the line of connection that the collar or breeching will not droop or sag and wrinkle or disfigure the straps by which the loop is attached to the harness; and, second, to so form the loop that it will not cause the supporting straps to chafe and disfigure the portion of the harness to which it is attached. I attain these objects by the device illustrated in the accompanying drawing, in which

Figure 1 is an elevation of a section of a breast collar to which this loop is attached, with a portion of the supporting strap and the trace broken away to show the form and application of the loop. Fig. 2 is an edge view of the same. Fig. 3 is a detached elevation of the loop; and Fig. 4 is an edge elevation of the same.

Similar letters refer to similar parts throughout the several views.

A represents a portion of a breast collar. B represents the end of a trace that is firmly sewed to the breast collar, and B' represents a retaining or supporting strap or loop, also firmly sewed, or otherwise attached to the breast collar. The end of the trace B, and, also, the end of the strap B' are folded to form a loop b b around each side stem of the loop C, and to avert all possible danger of the loop drawing upward on the extreme ends of the trace B and straps B' I form an arm D integral with each side stem of the loop, to extend out at right angles therewith, and longitudinal of the trace B and the strap B'. When the end of the trace and the strap are folded over to form the loops b b they are wrapped or folded around the side stems of the loop C with the arms D D between the folds, as shown in Fig. 2 and plainly indi-

cated in Fig. 1, and may be securely fastened to the lower laps of these loops and to the breast collar A by means of rivets d d, passing through the breast collar, the lower laps of 55 the loops and the arms D D of the harness loop C and riveted down, as indicated in Fig. 1. The loop C is made of metal and has holes d' d' formed through the arms D for the passage of the rivets d d, as hereinbefore 60 stated. After the loop C has been secured in the loops b b and to the breast collar A, as stated, the trace B on one side, and the strap B', on the other side of the loop C must be folded back and down and firmly stitched or 65 otherwise firmly attached to the breast collar A in such a manner that there will be a small amount of flexibility to the breast collar immediately back of the loop C. While it is not actually necessary to secure the arms 70 D D to the collar by the use of the rivets d d, I deem it much more efficient with their use as it greatly strengthens and stiffens the harness at this point.

For the purpose of holding the strap E and 75 the loop E' away from the surface of the collar A, to avert the danger of chafing the collar with this strap and loop, I curve the end C' of the loop C outward, as shown in Fig. 3, so that these parts move free of the surface 80 of the collar.

F represents a buckle that is attached to the strap E for the purpose of enabling me to attach the neck, or other supporting strap, not here shown, for supporting the collar 85 and traces of the harness.

This loop constructed with the arms D D removed and the loop secured to the collar by having the trace B wrapped around one side and the securing strap B' wrapped around 90 the other side and said trace and strap securely stitched to the collar would be much more effectual to prevent bending and wrinkling the collar at the point of support, than any other construction now in use, and would 95 prove a very desirable and satisfactory improvement in harness construction.

Having thus fully described my invention, what I claim as new, and desire to secure by Letters Patent of the United States, is:

In combination with a collar, a trace and a securing strap of a harness, a metal loop

formed with an integral arm projecting from each side, an end of the trace infolding one side of the loop and an end of the strap infolding the other side of the loop, rivets securing the arms of the loop to the collar, the trace and the strap infolding the arms and being securely stitched to the collar.

Signed at Grand Rapids, Mich., November 22, 1907.

ADOLPH W. KREUTER.

In presence of—
I. J. CILLEY,
G. A. HUTSON.
